UNITED STATES PATENT OFFICE

GEORGE A. PASTORE, OF CRANSTON, RHODE ISLAND

DESIGN FOR A BUCKLE

Application filed May 22, 1930. Serial No. 35,725. Term of patent 3½ years.

To all whom it may concern:

Be it known that I, GEORGE A. PASTORE, a subject of the King of Italy, residing at Cranston, in the county of Providence and State of Rhode Island, have invented a new, original, and ornamental Design for Buckles, of which the following is a specification, reference being had to the accompanying drawings, forming part thereof.

Fig. 1 is a top plan view of a design for a buckle showing my new design and comprising oppositely positioned extending

wings connected by a rectangular frame provided with a raised edge extending there-around, the frame portion being adapted to support an ornament, and,

Fig. 2 is an edge view of the buckle shown in Fig. 1.

I claim:

The ornamental design for a buckle, substantially as shown and described.

In testimony whereof I have affixed my signature.

GEORGE A. PASTORE.
